UNITED STATES PATENT OFFICE

127,919

DESIGN FOR AN AIRPLANE

Edward F. Burton, Los Angeles, and Carlos C. Wood, Santa Monica, Calif., assignors to Douglas Aircraft Company, Incorporated, Santa Monica, Calif.

Application July 14, 1939, Serial No. 86,004

Term of patent 7 years

To all whom it may concern:

Be it known that we, Edward F. Burton and Carlos C. Wood, citizens of the United States and residents of Los Angeles and Santa Monica, respectively, in the county of Los Angeles and State of California, have invented a new, original, and ornamental Design for an Airplane, of which the following is a specification, reference being had to the accompanying drawings, forming part thereof.

Figure 1 is a plan view of the subject airplane;

Figure 2 is a front elevational view of the airplane depicted by Figure 1;

Figure 3 is a side elevational view of the airplane depicted by Figure 2; and

Figure 4 is a bottom perspective view of the airplane in flight.

The dominant features of our airplane design reside in the portions shown in full lines in the drawings.

We claim:

The ornamental design for an airplane, substantially as shown and described.

EDWARD F. BURTON.
CARLOS C. WOOD.
